(57) **CLAIM**

The ornamental design of an insulator sleeve, as shown and described.

DESCRIPTION

FIG. 1 is a side view of the insulator sleeve in accordance with the invention shown on a coffee container, all side views are identical;

FIG. 2 is a top view thereof; and,

FIG. 3 is a bottom view thereof.

The container shown in broken lines represents environment only and forms no part of the claimed design.

1 Claim, 2 Drawing Sheets

FIG. 1

FIG. 2

FIG. 3
